(74) Attorney, Agent, or Firm — Ward & Zinna, LLC

(57) CLAIM

The ornamental design for a bottle, as shown and described.

DESCRIPTION

FIG. 1 is a top, front perspective view in accordance with the present invention;

FIG. 2 is a front elevational view thereof;

FIG. 3 is a rear elevational view thereof;

FIG. 4 is a right side elevational view thereof, the left side elevational view being a mirror image except for the unclaimed circular portion on the front sidewall; and,

FIG. 5 is a top plan view thereof.

The broken lines shown in the drawing views are included for the purpose of illustrating environmental structure that forms no part of the claimed design.

1 Claim, 5 Drawing Sheets
